United States Patent

Des. 237,185
Patented Oct. 14, 1975

237,185

COMBINED WATER CLOSET SEAT AND COVER

Robert O'Neil, Wheaton, Ill., assignor to Beneke Corporation, Columbus, Miss.

Filed May 10, 1974, Ser. No. 469,037

Term of patent 14 years

Int. Cl. D23—02

U.S. Cl. D23—71

FIG. 1

FIG. 2

FIG. 3

FIG. 1 is a top perspective view of a combined water closet seat and cover embodying my new design;

FIG. 2 is a bottom perspective view thereof; and

FIG. 3 is a top perspective view thereof, showing the cover in an open position.

I claim:

The ornamental design for a combined water closet seat and cover, as shown.
